CLAMP TIGHT SWITCH

Otto Jensen, Malvern, Pa., assignor to I. T. E.
Circuit Breaker Company, Philadelphia, Pa., a
corporation of Pennsylvania

Application April 30, 1946, Serial No. 665,947

5 Claims. (Cl. 290—170)

1

My present invention relates to switchgear and more particularly to double throw switchgear arranged to engage the movable contact with the stationary contacts in a tight clamping arrangement in each position of the double throw switch.

Heretofore in switchgear of the knife switch type, it has been customary to provide a clamping arrangement for interengaging the movable element of the knife switch with the stationary contact. A portion of the closing movement of the switch was used to bring the movable contact or blade up into registry with the stationary contact and the remaining movement of the switch handle performed the clamping action. This type of clamping action is shown in the Scott Patent 2,246,072, assigned to the assignee of the present invention.

However, the problem becomes more complex in double throw switches where the movable contact blade has a neutral position as well as two separate contacting positions 180° apart.

Various means have been attempted to provide for adequate clamping pressure at both contacting positions of the knife blade but these have resulted either in extremely complex duplicate clamping mechanisms or in having a clamped contact arrangement at one position only with the other position being subjected to only light clamping engagement.

In general, my invention contemplates the utilization of a single right hand thread screw member which will be actuated when the switch is closed in either direction to clamp the switch blades tightly across the contacts, although it will be understood that a left handed screw may be employed, if desired.

More specifically, my invention contemplates a clamp tight switch arrangement in which the movable contact carrying arm is mounted on a screw member threaded at both ends. The switch is a two-blade single pole switch and is so arranged that when the contact is moved into either of its contact engaging positions, it is clamped against the stationary contact members.

When the contact member is in one of its contact engaging positions, the screw member is rotated clockwise. Clockwise rotation causes the screw to react on a nut at one end as at the left end through the nut to compress the contact member against the stationary contact, the direction of the clamping force being opposite to the direction of axial movement of the screw member.

The same clockwise rotation of the screw member causes the other end of the screw to directly compress the movable contact against the opposite side of the fixed contact, the force being in the same direction as the axial movement of the screw member.

2

When the movable contact is moved to its opposite pole, the screw member is rotated counterclockwise. Counterclockwise rotation of the screw member causes the screw to rotate on the nut located on the opposite side from the above described nut, namely, on the right hand and through this other nut to compress the movable contact against the fixed contact in a direction opposite to the axial movement of the screw member. The same counterclockwise rotation causes the other end of the screw member to directly compress the movable contact against the fixed contact into the same direction as the axial movement screw member.

Summarizing the above, a screw member arrangement is thus provided which clamps a movable contact against one of its two pole terminals when the movable contact is rotated clockwise and clamps it against the other of its two pole terminals when the movable contact is moved into opposite counterclockwise direction.

Accordingly a primary object of my present invention is to provide a simple clamping mechanism primarily for a double throw knife type switch wherein a single clamping member and single operating means therefor is effective to create proper contact engaging clamping pressure at both contact closing positions of the knife switch.

Another object of the present invention is the provision of clamping means for a double throw knife type switch wherein the clamping means is released when the switch blade is in neutral intermediate position but wherein the clamp is operated to engaged position on movement of the switch handle in either direction from the neutral.

The foregoing and many other objects of my invention will become apparent in the following description and drawings in which

Figure 1 is a side view showing the general operation of my novel clamping means for a double throw knife type switch.

Figure 2 is a bottom view of the switch handle taken from line 2—2 of Figure 1.

Figure 3 is an end view of the latch means for the switch handle taken from line 3—3 of Figure 1.

Figure 4 is a front view of the switch of Figure 1 in the upper connected position with the handle assembly partly broken away.

Figure 5 is a cross-sectional view taken from line 5—5 of Figure 1 and showing the arrangement of the clamping mechanism when the switch is closed against the upper stationary contact.

Figure 6 is a view corresponding to that of Figure 5 showing the arrangement of the clamping mechanism when the switch is open with the switch handle in neutral position.

Figure 7 is a view corresponding to that of Figure 5 showing the arrangement of the clamping mechanism with the switch closed and in engagement with the bottom switch contact.

Referring now to Figure 1, my novel double-throw knife type switch 10 is mounted on an insulating panel 11 which carries the upper stationary contact terminal 12 and the lower stationary contact 13. Contact terminals 12 and 13 are supplied with special conductive alloy buttons 14, 14 and are part of the conductive back connection studs 15, 16 which pass through appropriate openings 17, 18 respectively in the insulating panel 11.

The movable contact assembly 25 is rotatably mounted on the central terminal block 26 which in turn is conductively secured to the back connection stud 27 which passes through opening 28 in insulating panel 11. Terminal block 26 carries the pair of upper link members 30 and the pair of lower link members 31 pivotally secured thereto at pivots 33 and 34, respectively. The opposite ends of the pair of arms 30 are pivotally secured by the rivets 35 to the clamp plate 75 hereinafter described. The lower arms 31 are similarly pivotally secured by the rivets 36 to the clamping plate 75.

My novel device is so arranged, as hereinafter described, that the contact plates or blades 40, 40' are bridged and clamped across terminal 26 and contact terminal 12 in the upper closed position of the switch, and across terminal 26 and contact terminal 13 in the lower closed position of the switch; but that in any intermediate position, the plates or blades 40, 40' will be spaced apart sufficiently so that they may readily move from one contact bridging position to the other.

In operation, when the switch is in the up position of Figure 1, the initial downward movement of handle 41 will release the clamp which holds the contact plates 40, 40' tightly against the stationary contact 12 and terminal 26. Subsequent downward movement of handle 41 will move the contact plates 40, 40' down to the neutral dotted line position shown in Figure 1. Still further downward movement of handle 41 will bring the contact plates 40, 40' into registry with the lower stationary contact 13 and terminal 26. The final downward movement of handle 41 will clamp the contact plates 40, 40' tightly against the lower contact 13 and the terminal 26.

The entire clamping action is accomplished by a single clamping screw hereinafter described which screw will effect the clamping operation when it is turned clockwise with respect to Figure 1 when the switch handle 41 is raised; and counterclockwise with respect to Figure 1 as the switch handle 41 is lowered to the down position.

The switch handle 41 is, as shown in Figure 2, secured in any suitable manner to the bracket 43, which bracket 43 is mounted for limited rotation on the pin 45 carried between the side members 46, 47 of the handle assembly. The side members 46, 47 are spaced from each other by the spacer piece 48 to which they are secured by rivets 49, 49.

Latches 50 and 51 are also rotatably mounted on pin 45 and are each provided with latch tip elements 52, 53 respectively and dog leg portions 54, 55 respectively. Dog leg portions 54, 55 of latches 50 and 51 extend up on either side of pin 60 which is carried between the plates of bracket 43.

When the handle 41 and the entire movable contact assembly 25 are raised to the upper con-

tacting position, latch tip 52 of latch 50 engages the keeper 62 at the top of stationary contact element 12. Similarly when the handle 41 and the movable assembly 25 are in the lower position, latch tip 53 of latch 51 engages the keeper 63 on the lower stationary contact 13. These latches thus prevent the handle assembly, including the movable contact, from dropping down or being physically shocked out of engaged position and thus actually relieving the clamping pressure on the contact blades 40, 40'. These latches also prevent the blade from being blown off in case of excessively high current.

When, however, with the elements shown in Figure 1, handle 41 is pulled down, pin 60 bears against dog leg 54 of latch 50 and rotates latch 50 counterclockwise to disengage latch tip 52 from keeper 62. Further downward movement of handle 41 brings the latch 50 against the stop member 65 to prevent further movement of handle member 41 and bracket 43 around the pin 45 so that the entire handle assembly now rotates counterclockwise about the clamping screw 70 to release the clamping pressure on the bridging blades 40, 40'.

Similarly, when the lower contact 13 is engaged, a lift of handle 41 will first cause pin 60 to engage dog leg 55 of latch 51 to disengage latch tip 53 from keeper 63 and subsequent lifting of handle 41 causes latch 51 to bear against the opposite side of member 65 so that further lifting of handle 41 causes the handle assembly to rotate upwardly around the clamping screw 70 to release the clamping pressure on the bridging blades 40, 40', central terminal block 26 and the lower terminal 13. The movement of the entire contact assembly 25 around pivots 33 and 34 is in addition to the movement of the plates 46, 47 around the center of clamp operating screw 70 hereinafter described.

The back ends of plates 46 and 47 have mounted between them the projection 66 biased toward the right with respect to Figure 1 by the compression spring 67. Member 65 previously described has an extension 68 provided with a hook 69 engaging pin 71 on projection 66.

When the contact assembly 25 is in the neutral central position shown by dotted lines in Figure 1, projection 66 is pressed by the compression spring 67 into the notch 72 of the central extension 73 of the terminal 26, mounted on the front of panel 11 and thus maintains the entire movable contact 25 in neutral position.

When the handle 41 is lifted from the neutral position, the pin 60 bears against dog leg 55 of latch tip 51 which in turn pulls out member 65 thus pulling on extension 68 and hook 69, thereby pulling on pin 71 of projection 66 to disengage projection 66 from the notch 72.

As soon as projection 66 is disengaged from notch 72, further lifting of the handle moves the entire contact assembly 25 up. When the entire contact assembly reaches the up position with contact blades 40, 40' engaging the upper contact 12 and terminal 26, further upward movement of the assembly 25 rotates the clamping screw 70 thus clamping the blades 40, 40' tightly against the upper contact 12 and the terminal 26 as hereinafter more fully described.

The same action occurs, of course, during downward movement of the contact assembly 25 toward 13.

Thus the movable contact assembly 25 when it is in any of the three positions above set forth actually has three centers of rotation. First the

handle 41 and its bracket 43 rotate about pin 45 to disengage either the latch 50 or 51 depending on whether contact is made at the top or bottom; or to disengage projection 66 should the contact assembly be in neutral position. Second, the contact assembly is then rotated to its next position about the centers 33 and 34. Thirdly, after either contacts 12 or 13 have been engaged, the handle assembly rotates about the screw 70 to clamp the contact blades 40, 40' against either of the stationary contacts 12 or 13 and terminal 26.

The first and second centers of rotation (pin 45 and pivots 33 and 34) have already been described both as to characteristics and operations. The operation of the third center of rotation (about screw 70) in order to clamp the movable contact blades 40 against either of the stationary contacts is shown more specifically in connection with Figures 5, 6 and 7.

Figure 5 shows the position of the elements with the contact assembly in current carrying engagement with the upper stationary contact 12.

Figure 6 shows the same assembly with the elements in the neutral or dotted line position of Figure 1.

Figure 7 shows the position of the elements with the movable contact assembly engaged with the lower stationary contact 13.

Each of the pair of movable contact blades 40 and 40' is provided with a flexible metallic spring-like clamping plate 75, 75'. The clamping nuts 76 and 76' bear against the clamping plates 75 and 75' in order to exert pressure on the blades 40 and 40'. The clamping nuts 76 and 76' are adjusted and locked by set screws 78, 78' registering and engaging some of the notches 79, 79' of each of the nuts 76, 76'; the set screws being threaded into appropriate threaded openings in the clamping plates 75, 75'.

It should first be pointed out that the clamping screw 70 is a right hand threaded screw and that this single screw is utilized to perform the clamping function at both the top and bottom position. The advantage of this type of construction lies in the fact that right hand threads are standard practice in the manufacture of screws and thus eliminates the necessity for a special machining operation requiring composite threading; and also the arrangement shown in Figures 5, 6 and 7 is such that for the first time a clamping action is accomplished by rotating an ordinary right-hand clamping screw in either a clockwise or counterclockwise direction. It will be understood, however, that a left-hand screw may be used or a double threaded screw at opposite ends may be employed for direct action in place of the reaction on the nut.

The side members 46 and 47 are, in addition to their being riveted to the spacer block 48, further supported by reason of the fact that the ridges 80 and 81 in the side member 46 cooperate with a corresponding depression 82 in the spacer washer 83. Spacer washer 83 has a corresponding ridge 84 on its opposite side which cooperates with a groove 86 in the counterbore 87 of switch blade 40'.

The compression spring 90 surrounding the screw 70 passes through an opening 91 in switch blade 40 and bears at one end against the clamping plate 75 and at the opposite end against the outer surface of handle plate 47 to bias the assembly consisting of handle plates 47 and 46 with their associated elements as well as the spacer washer 83 to the right. Counterbore 87 in switch

blade 40' is concentric with opening 91 in the switch blade 40'.

With all of the elements biased to the right and interengaged as shown in Figure 6, the ridge 5 81 of handle plate 46 engages recess 82 of spacing washer 83; and ridge 84 of spacing washer 83 engages the notch or recess 86 in the annular plane surface of counterbore 87 of opening 91' of switch blade 40'.

The handle plates 46 and 47 are keyed to the clamping screw 70. Clamping screw 70 is a substantially cylindrical member as shown having a squared portion 70c. Plates 46, 47 are provided with matching square openings receiving the 15 squared portion 70c of the member 70. Clamping screw 70 is provided with the threaded end 70a engaging the threads of nut 76 and the threaded end 70b engaging the threads of nut 76'.

When the movable contact assembly 25, including the handle plates 46 and 47, has moved the blades 40 and 40' to the upper contacting position, the blades 40, 40' and the clamping plates 75, 75' can no longer move clockwise. Thereafter further lifting of the handle 41 rotates 25 the screw 70 in a clockwise direction, with respect to Figure 1.

This rotation about the center of screw 70 occurs after the entire assembly has been rotated around the pivots 33 and 34 to the upper bridging position. This rotation now unwinds the threaded end 70b of clamping screw 70 from the right-hand clamping nut 76', and turns the threaded end 70a into the left-hand clamping nut 76, Figure 5.

35 Since the clamping nuts 76 and 76' are prevented from rotating by the set screws 78, 78', the entire handle assembly including handle plates 46 and 47 and the screw 70 will be moved axially to the left and cause the left-hand clamping nut 76 to bear against the face of clamping plate 75.

40 This in turn draws the right-hand clamping washer 95', which is captured in shouldered recess 96' in the right-hand end of the screw 70, 45 toward the left against the outer face of the right-hand clamping plate 75'.

In this position the corresponding left-hand clamping washer 95 in recess 96 of left-hand end of the screw 70 is loose.

Thus, the further rotation of screw 70 above described will draw the clamping plates 75, 75' together to exert clamping pressure on blades 40, 40' and drive the blades into tight clamping engagement with contacts 12 and 26.

55 This pressure is obtained as shown by clamping nut 76 firmly engaging clamping plate 75 and by clamping washer 95' firmly engaging clamping plate 75'.

The reverse or opposite action of the above procedure takes place when the handle assembly is moved downwardly as shown in Figure 7. Here the screw 70 is turned counterclockwise with respect to Figure 1 and draws the right-hand clamping nut 76' against the right-hand clamping plate 75' and the left-hand clamping washer 95 against the left-hand clamping plate 75, thereby exerting clamping pressure on the switch blades 40, 40'.

The entire assembly is released and returns to neutral position as shown in Figure 6 on movement of the switching members from the position of Figure 5 or the position of Figure 7 (the up or down positions) toward the central or neutral position.

70 By means of the foregoing it will thus be seen

that a single member having ordinary simply machined right-hand threads at each end may readily be used to provide an effective clamp for a double throw knife blade type switch wherein the bridging or connecting blades are effectively clamped at both the upper and lower positions.

In the foregoing I have described my invention solely in connection with a specific preferred embodiment thereof. Since many variations and modifications of my invention should now be obvious to those skilled in the art, I prefer to be bound not by the specific disclosure herein contained, but only by the appended claims.

I claim:

1. In a switch mechanism, a contact having two terminals, screw means, means for operating said contact to either of its terminals, said screw means thereafter clamping said contact into engagement with the terminal to which it has been operated, said screw means being rotatable clockwise for effecting clamping engagement with one of said terminals and rotatable counterclockwise for effecting clamping engagement with the other of said terminals, a nut and washer provided on opposite ends of said screw means, said screw means reacting on the nut on one end to produce a force in the opposite direction from the axial movement to said screw means and acting on the washer at the opposite end to produce a force in the same direction as the axial movement of said screw member.

2. In a switch mechanism, a contact having two terminals, a screw member, means for operating said contact to either of its terminals and means for thereafter clamping said contact into engagement with the terminal to which it has been operated, said screw member being rotatable clockwise for effecting clamping engagement with one of said terminals and rotatable counterclockwise for effecting clamping engagement with the other of said terminals, a nut and washer provided on opposite ends of said screw member, said screw member reacting on the nut on one end to produce a force in the opposite direction from the axial movement of said screw member and acting on a washer at the opposite end to produce a force in the same direction as the axial movement of said screw member, and said screw member when the contact engages the opposite terminal acting on the opposite nut to set up a force opposite to the axial movement of said screw member and acting on the opposite washer to produce a force in the same direction as the direction of axial movement of said screw member.

3. In a clamp tight switch, a pair of terminals, a switch blade operable clockwise to engage one of said terminals and operable counterclockwise to engage the other of said terminals, a screw member rotatable clockwise by said blade when it is operated to engage one of said terminals and counterclockwise with said switch blade when said switch blade is operated to engage the other of said terminals, and means controlled by said screw member for clamping said switch blade against the terminal with which it is engaged, said means including nuts on the ends of said screw member, said screw member in one direction of rotation compressing the blade against the terminal through one of said nuts, the direction of clamping being opposite to the direction of axial movement of said screw member.

4. In a clamp tight switch, a pair of terminals, a switch blade operable clockwise to engage one of said terminals and operable counterclockwise to engage the other of said terminals, a screw

member rotatable clockwise by said blade when it is operated to engage one of said terminals and counterclockwise with said switch blade when said switch blade is operated to engage the other of said terminals, and means controlled by said screw member for clamping said switch blade against the terminal with which it is engaged, said means including nuts on the ends of said screw member, said screw member in one direction of rotation compressing the blade against the terminal through one of said nuts, the direction of clamping being opposite to the direction of axial movement of said screw member, and the same direction of rotation of said screw member causing the other end of said screw to directly compress the blade against the opposite side of said terminal.

5. A double throw switch comprising a first contact, a second contact, a switch arm carrying a contact and having a neutral position and movable in one direction to engage said first contact and in the opposite direction to engage said second contact, a screw member threaded at both ends and having a first and second nut at opposite ends operable when said switch arm is operated in either direction to clamp said arm against its engaged contact, said movable switch arm being mounted in said screw member, said screw member being rotated in one direction, after said switch arm contact engages said first contact and reacting on said first nut at one end to compress the contact in said switch arm against the first contact, the direction of clamping force being opposite to the direction of axial movement of said screw member, the same direction of rotation of said screw member causing the other end of said screw to directly compress the movable contact in said switch arm against the first contact, the force being in the same direction as the axial movement of the screw member, said screw member being rotated in the opposite direction, after said switch arm contact engages said second contact, and reacting on said second nut at the other end to compress the contact on said switch arm against said second contact, the direction of clamping force being opposite to the direction of axial movement of said screw member, the same last mentioned direction of rotation of said screw member causing the other end of said screw member to directly compress the movable contact in said switch arms against the second contact, the force being in the same direction as the axial movement of the screw member.
